ELECTROMAGNETIC APPARATUS

Carl G. Kronmiller, Minneapolis, Minn., assignor
to Minneapolis-Honeywell Regulator Company,
Minneapolis, Minn., a corporation of Delaware

Application May 28, 1936, Serial No. 82,217

15 Claims. (Cl. 200—112)

My invention pertains to electromagnetic apparatus and more particularly to electromagnetic switching apparatus.

In the ordinary electromagnetically operated instruments wherein an element to be actuated is biased to one position and is moved to a second position by energization of a winding, it is necessary for a considerable voltage drop to occur before the winding is sufficiently deenergized for the device to return to its original position. Where the electromagnetic device is an electromagnetically operated switch employed as a relay in a control circuit, this may have a very decided disadvantage. Thus in the case of a control system for a fluid fuel burner, such as an oil burner, wherein electrical ignition means is employed, it is undesirable for a motor to remain energized after the voltage drops to the point where the ignition means is rendered inoperative. Accordingly, it becomes highly desirable in such a system that the relay controlling the burner motor and the ignition means operates on a relatively low differential in voltage so that the relay will open both the motor and ignition circuits before the voltage has dropped to a point where the ignition means is rendered inoperative.

The object of the present invention is to provide a relay which will operate on such a low differential in voltage. The invention, accordingly, resides in the various features of the switching apparatus by which such operation is obtained. Moreover, while certain features of the device are of particular value in such a low voltage release relay, they are of general utility in any electromagnetically operated device.

The various novel features of my electromagnetically operated switch will be apparent from a consideration of the accompanying specification, claims and drawing, of which—

Figure 1 is a view partly in section of my improved electromagnetic apparatus.

Figure 2 is an elevational view taken in the direction of the arrow 2 of Figure 1, and in which

Figure 3 is a schematic view of a control system employing my novel electromagnetic apparatus as a relay.

Referring to Figures 1 and 2, the winding of the relay is designated by the reference numeral 11. This winding or coil is provided with a passage therethrough in which is placed an insulating sleeve 12. Insulating washers 13 and 14 are placed on the opposite ends of the winding. On each side of the coil is an end plate 16 of suitable magnetic material, such as steel. Extending 55 through the passage of the winding 11 inside of

the sleeve is a sleeve 15 of non-magnetic metal whose ends are overturned at 17 to clamp the plates 16 firmly against the coil and to hold the various elements previously set forth in assembled relation. Extending around the coil 11 on three sides thereof is a member 20 of magnetic material, such as steel. The member 20 is formed of sheet metal and is bent as shown in Figure 2 to form a U-shaped casing member which is secured to the end plates 16 through cooperating lugs and slots 21. The U-shaped casing member 20 together with the plates 16 form a magnetic casing around the coil enclosing the same on all but one side. Member 20 terminates in two apertured lugs 23 and 24 which serve for mounting 15 the apparatus in a position such that the passage through the coil is horizontal.

Spaced lugs 25 and 26 are struck up from the upper leg of U-shaped member 20 to form mounting means for a second U-shaped member 27. U-shaped member 27 is pivotally mounted on the lugs 25 and 26 through downwardly extending lugs 28 and 29 and a pivot pin 30 which extends through lugs 25, 26, 28 and 29. One end of pin 30 is upturned as at 31 and the other end is provided with an eye 32 which serves to guide conductors leading to a switch to be presently described.

The U-shaped member 27 comprises a base portion 35 and two downwardly extending legs 36 and 37 which legs are disposed on opposite sides of the passage through coil 11. This member is made of suitable non-magnetic material, such as brass, so as not to affect the operation of the relay. Secured to the two legs 36 and 37 is a core comprising a portion 38 of magnetic material and a second portion 39 of non-magnetic material. The two portions 38 and 39 are in abutting relationship and are held assembled by a screw 40 of non-magnetic material, such as brass, which also serves to secure one end of the core to leg 36. A second screw 41 secures the other end of the core to leg 37. A series of washers 43 are secured to one leg of U-shaped member 27 through a screw 44 and constitutes a weight serving to bias the U-shaped member and the attached core to the position shown in Figure 1. It will be readily seen that the magnetic center of the core which corresponds to the center of portion 38 thereof is displaced from the center of coil 11 so that upon energization of coil 11 a force will be exerted tending to move core 38 to the right and to hence rotate member 27 in a counter-clockwise direction about its pivot pin 30. A leaf spring 48 is secured at one end to 55

leg 37 of U-shaped member 27 and terminates at its lower end in a projecting portion 49 which engages the end plate 16 against which it is adjacent, upon energization of the winding 11. The spring 48 is preferably sufficiently stiff that it will prevent the core 38 moving to the right sufficiently to move the leg 37 of member 27 against the end plate 16. This is especially important for use with alternating current inasmuch as there is inevitably a certain fluctuation in the flux to which the core is subject and if the relatively rigid leg 37 is allowed to engage with end plate 16, the fluctuation in the flux will cause a chattering between leg 37 and end plate 16.

Secured on the base 35 of U-shaped member 27 is a clip member 51, which clip member serves to retain a mercury switch 52. This mercury switch 52 may be of any conventional type but is shown for purposes of illustration as comprising an envelope 53 of glass or similar material in which is housed spaced electrodes 54 and 55. Located within the envelope 53 at a depth to contact with said electrodes 54 and 55 is a quantity of mercury 56 which mercury upon switch 52 being tilted in a counter-clockwise direction is adapted to engage electrodes 54 and 55. Secured to the electrodes 54 and 55 are suitable conductors 58 and 59 which extend through eye 32 of pin 30 to any desired apparatus controlled by the switch.

Due to the fact that there is always an air gap between the core and the winding 11, the force exerted upon core 38 as the same is moved inwardly does not increase as rapidly as in the type of electromagnetically operated apparatus wherein the armature is moved into engagement with magnetic material associated with the winding. While the pull on the core 38 does increase to some extent as the core 38 is moved inwardly, this increase in pull is rather small. As a result only a relatively small drop in voltage below the value necessary to move core 38 sufficiently to close the mercury switch 52 is necessary before core 38 is returned to its original position by the action of biasing washers 43. This action is aided by the leaf spring 48 which serves to exert a force to energize the return movement of core 38 upon the complete or partial deenergization of winding 11. The operation of the device by a relatively low voltage differential is also facilitated by reason of the fact that the mercury switch 52 requires a relatively small movement to open and close the same. It will further be noted that the various advantages obtained by this apparatus are obtained through the use of a relatively simple construction, the major portions of which are constructed out of sheet metal stampings. In this manner an extremely cheap apparatus is afforded which operates at a relatively low voltage differential.

In Figure 3 of the drawing, there is shown a control system employing my device as a relay to open the circuit in the event of the voltage of the power supply assuming a low value. In this figure, a burner motor is generally designated by the reference numeral 70. This motor may be employed for the purpose of forcing a combustible mixture of oil to a burner nozzle from an oil burner. Designated by the reference numeral 71 is any suitable ignition means. This means may conveniently take the form of a high voltage spark gap, although the particular form which it takes forms no part of the present invention.

A room thermostat is generally designated by the reference numeral 72. This thermostat comprises a bimetallic element 73 to which are at-

tached contact arms 74 and 75 which carry contacts 76 and 77 which are adapted to be engaged with contacts 78 and 79. Contacts 76 and 78 are more widely spaced than contacts 77 and 79 so that upon deflection of the contact arms 74 and 75 to the left by reason of the temperature to which bimetal element 73 is subjected decreasing, the contacts 77 and 79 are moved into engagement before contacts 76 and 78.

A step-down transformer 80 is employed to supply low voltage power for the operation of the control system. This transformer comprises a line voltage primary 81 connected to suitable line wires 82 and a low voltage secondary 83.

Designated generally by the numeral 85 is a thermal safety switch which may be of any suitable form but is preferably of the form shown in the patent to F. S. Denison No. 1,958,081, of May 8, 1934. For purposes of illustration, this switch is shown as comprising two switch arms 86 and 87 carrying cooperating contacts 88 and 89. Contact arm 87 is biased away from contact arm 86 but is held in engagement therewith by a bimetallic element 90 which normally engages the underside of switch arm 87. Upon heating of bimetallic element 90, it is caused to deflect to the right and if such deflection is carried sufficiently far, it will move beyond switch arm 87 permitting the separation of switch arms 86 and 87. Associated with the bimetal element 90 is an electrical heating element 91.

Generally designated by the reference numeral 93 is a stack switch which may take any usual form. Such switches normally comprise a bimetal element which extends into the stack and is operatively connected to one or more switches through a slip friction connection. For purposes of illustration, this stack switch is shown as comprising a bimetal element 94 adapted to cooperate with the fixed overlapping contacts 95 and 96. The bimetal element is so constructed that it is caused to deflect to the right upon an increase in temperature and towards the left upon a decrease in temperature. When there is no combustion in the furnace, the element 94 engages 95 but upon the presence of combustion in the furnace, the element moves into engagement with contact 96.

A relay is designated by the reference numeral 100. This relay comprises a relay coil 101 and a plurality of relay arms 102, 103 and 104 which are adapted to engage contacts 105, 106 and 107, respectively. The relay arms are biased away from their respective contacts and are adapted to be moved into engagement therewith through energization of relay coil 101.

The electromagnetic switch of the present invention is designated by the legend "Low voltage release relay", which legend indicates its function in this circuit as will be more apparent from the following description of the operation therein. The various elements of the device bear the same reference characters as used in connection with the description of the operation of Figures 1 and 2 and further explanation thereof in connection with this figure is deemed unnecessary. It will be noted that the relay coil 102 is permanently connected to line wires 82 through conductors 118, 119 and 120. Accordingly, so long as the line voltage is near its normal value, coil 102 is sufficiently energized to hold the core of the switch in its extreme right-hand position and to hence keep the mercury switch 52 tilted at such an angle that electrodes 54 and 55 are bridged by mercury 56.

The various elements are in the position shown when the temperature in the space heated by the burner is above the desired value. Upon a decrease in temperature occurring, contact arms 5 74 and 75 will be deflected to the left by bimetal element 73 causing first the engagement of contacts 77 and 79. The engagement of these contacts will not however, cause the establishment of any energizing circuit. Upon the drop in temperature being carried sufficiently far, the engagement of contacts 76 and 78 will be effected. Upon such engagement taking place the following circuit will be established to relay coil 101: from the right-hand terminal of secondary 83 through conductor 110, contacts 79 and 77, contact arms 15 75 and 74, contacts 76 and 78, conductors 111 and 112, electrode 54, mercury 56, electrode 55, conductor 113, bimetal element 94, contact 95, conductor 114, heating element 91, conductor 115, relay coil 101, conductor 116, switch arm 87, contacts 89 and 88, switch arm 86, and conductor 117 back to the left side of secondary 83. The energization of relay coil 101 causes switch arms 20 102, 103 and 104 to be moved into engagement with contacts 105, 106 and 107 against the action of the biasing means.

The engagement of switch arm 103 with contact 106 establishes the following holding circuit for relay coil 101: from the right-hand terminal of secondary 83, through conductor 110, contacts 79 and 77, contact arm 75, bimetal element 73, conductor 121, contact 106, relay arm 103, conductors 122 and 112, electrode 54, mercury 56, electrode 55, conductor 113, bimetal element 94, contact 95, conductor 114, heating element 91, conductor 115, relay coil 101, conductor 116, switch arm 87, contacts 89 and 88, switch arm 86 and conductor 117 to the other terminal of secondary 83. It will be noted that the circuit just traced is independent of the engagement of contacts 76 and 78 so that in the event of a very slight temperature rise the operation of the system will not be stopped. Due to the fact that there is a greater space between contacts 76 and 78 than contacts 77 and 79 and due to the fact that the system is not placed into operation until contacts 76 and 78 engage and is not placed out of operation until contacts 77 and 79 disengage, a differential is provided which prevents a hunting action or frequent starting and stopping of the burner caused by a chattering of the thermostatic contacts.

The moving into engagement of relay arm 104 with contact 107 causes the following circuit to be established to the burner motor 70: from one of the line wires 82 through conductor 118, contact 107, switch arm 104, conductor 120, conductor 125, burner motor 70 and conductor 126 to the other line wire 82. At the same time the following circuit to the ignition means is also established: from one of the line wires 82 through conductor 118, contact 107, relay arm 104, conductors 124 and 127, ignition means 71, and conductor 128 to the other line wire 82.

The establishment of these two circuits causes fuel to be supplied to the burner and at the same time starts the operation of the ignition means. The result is that under normal conditions the fuel issuing from the burner nozzle will be ignited and the furnace will be placed into operation. Upon such combustion taking place, hot gases will pass up the stack causing the bimetal element 93 to be deflected to the right in a very short space of time, causing the engagement thereof with contact 96. Upon such taking place,

the following new circuit is established: from the right-hand terminal of secondary 83 through conductor 110, contacts 79 and 77, contact arm 75, bimetal element 73, conductor 121, contact 106, relay arm 103, conductors 122 and 112, electrode 54, mercury 56, electrode 55, conductor 113, bimetal element 94, contact 96, conductor 129, relay arm 102, contact 105, conductor 130, relay coil 101, conductor 116, switch arm 87, contacts 89 and 88, switch arm 86 and conductor 117 to 10 the other terminal of secondary 83. Shortly after the circuit just traced is established, the bimetallic element will separate from contact 95 thus breaking the two circuits previously traced. It will be noted that the circuit just traced is 15 independent of the heater 91 so that energy is no longer supplied thereto. Thus, the bimetallic element 93 is no longer subjected to the heat therefrom and switch arms 86 and 87 remain in the position shown wherein contacts 80 and 89 20 are in engagement.

In the event, however, that combustion for some reason or other should not take place, hot gases will not pass up the stack and bimetal element 94 of stack switch 93 will remain in the 25 position shown in the drawing wherein it is in engagement with contact 95. The result will be that all of the current to relay coil 101 continues to pass through heating element 91 causing the same to eventually heat the bimetal element 90 30 sufficiently to cause separation of switch arms 86 and 87 deenergizing the entire system. The size of the heater 91 and the sensitivity of the bimetal element 90 can be so proportioned that switch arms 86 and 87 will be open after any desired 35 period of time. In this manner there is an assurance that the burner will not continue in operation in event of combustion failing to take place. Moreover, inasmuch as the stack switch will return to the cold position at any time if 40 combustion is accidentally terminated, this insures the deenergization of the system at any time that combustion is interrupted.

It will be noted that all of the circuits through relay coil 101 which have been traced during the 45 previous portion of the description depended upon the engagement of mercury 56 with electrodes 54 and 55. As previously pointed out, this engagement will occur only so long as the voltage across line wires 82 does not drop below a pre-determined value. In the event of this voltage assuming a value sufficiently low that there is 50 danger of the ignition means no longer functioning, the core of the relay will be released causing the mercury 56 to separate from electrodes 55 54 and 55, thus breaking all of the previously traced circuits through relay 101 and terminating the operation of the apparatus. Due to the relatively small differential between the value of voltage necessary to cause the relay to close 60 switch 52 and that at which switch 52 is opened, it is possible to insure that the operation of the burner motor will be terminated before the voltage drops to a dangerously low value.

While the above described application of my 65 electromagnetic apparatus is one of the advocations for which it is particularly designed, it is to be understood that this apparatus is of general utility wherever it is desired to have electromagnetically operated devices which must operate on a relatively low voltage differential. Moreover, as previously pointed out, there are 70 various features of construction in my device which are of general utility in any type of electromagnetically operated device.

While I have shown a certain specific embodiment of my device, it is to be understood that this is for purposes of illustration only and that my invention is to be limited only by the scope of the appended claims.

I claim as my invention:

1. In combination, a winding having a passage therethrough, means for mounting said winding with said passage horizontally disposed, a rigid U-shaped member having its base portion pivotally mounted above but close to said winding with its legs extending downwardly, a core comprising magnetic material extending through said passage and secured to the legs of said U-shaped member, means biasing said member to a position wherein the magnetic center of said core is displaced from the center of said winding, said winding being effective upon energization thereof to move said core and said member so as to cause the magnetic center of said core to approach the center of said winding, and means actuated by said member when so moved.

2. In combination, a winding having a passage therethrough, means for mounting said winding with said passage horizontally disposed, a rigid U-shaped member having its base portion pivotally mounted above but close to said winding with its legs extending downwardly, a core comprising magnetic material extending through said passage and secured to the legs of said U-shaped member, means biasing said member to a position wherein the magnetic center of said core is displaced from the center of said winding, said winding being effective upon energization thereof to move said core and said member so as to cause the magnetic center of said core to approach the center of said winding, a switch associated with said member, said member being effective upon movement thereof by the core to move said switch from one circuit controlling position to a second circuit controlling position.

3. In combination, a winding having a passage therethrough, means for mounting said winding with said passage horizontally disposed, a rigid U-shaped member having its base portion pivotally mounted above but close to said winding with its legs extending downwardly, a core comprising magnetic material extending through said passage and secured to the legs of said U-shaped member, means biasing said member to a position wherein the magnetic center of said core is displaced from the center of said winding, said winding being effective upon energization thereof to move said core and said member so as to cause the magnetic center of said core to approach the center of said winding, a switch having a fluid contact making member mounted on said U-shaped member, said member being effective upon movement thereof by the core to change the circuit controlling position of said switch.

4. In combination, a winding having a passage therethrough, means for mounting said winding with said passage horizontally disposed, a rigid U-shaped member having its base portion pivotally mounted above but close to said winding, a core comprising magnetic material extending through said passage and secured to the legs of said U-shaped member, means biasing said member to a position wherein the magnetic center of said core is displaced from the center of said winding, said winding being effective upon energization thereof to move said core and said member so as to cause the magnetic center of said core to approach the center of said winding.

5. In combination, a winding having a passage therethrough, means for mounting said winding with said passage horizontally disposed, a rigid U-shaped member having its base portion pivotally mounted above but close to said winding, a core comprising a portion of magnetic material and a portion of non-magnetic secured together in end to end relationship, said core extending through said passage and secured at its ends to the opposite legs of said U-shaped member, means biasing said member to a position wherein the center of the magnetic portion of said core is displaced from the center of said winding, said winding being effective upon energization thereof to move said core and said member so as to cause the center of the magnetic portion of said core to approach the center of said winding, and means actuated by said member when so moved.

6. In combination, a winding having a passage therethrough, means for mounting said winding with said passage horizontally disposed, a rigid U-shaped member having its base portion pivotally mounted above but close to said winding, a core comprising magnetic material extending through said passage secured to the legs of said U-shaped member, a weight secured to one leg of said member and effective to bias said member to a position wherein the magnetic center of said core is displaced from the center of said winding, said winding being effective upon energization thereof to move said core and said member so as to cause the magnetic center of said core to approach the center of said winding, and means actuated by said member when so moved.

7. In combination, a coil having a passage therethrough, end plates on opposite sides of said coil, a U-shaped member of sheet material extending around said coil and secured to said plates to form with the latter a casing for said coil, a second rigid U-shaped member pivotally mounted on said first member, a core extending through said passage and secured to the opposite legs of said second U-shaped member, said coil being effective upon energization thereof to cause movement of said core and consequently said member, and means actuated by such movement.

8. In combination, a coil having a passage therethrough, perforated end plates on opposite sides of said coil with their perforations in alignment with said passage, a sleeve extending through said passage and having its ends bent over and overlying said plates to clamp the same against said coil, a U-shaped member of sheet material extending around said coil and secured to said plates to form with the latter a casing for said coil, said member having portions struck outwardly to provide spaced lugs, a second U-shaped member pivotally secured to said lugs and disposed with the legs thereof opposite said passage, a core comprising magnetic material extending through said passage, and secured to the opposite legs of said second U-shaped member, and means to be actuated associated with said second U-shaped member.

9. In combination, a coil having a passage therethrough, perforated end plates on opposite sides of said coil with their perforations in alignment with said passage, a sleeve extending through said passage and having its ends bent over and overlying said plates to clamp the same against said coil, a U-shaped member of sheet material extending around said coil and secured to

5 said plates to form with the latter a casing for said coil, said member having portions struck outwardly to provide spaced lugs, a second U-shaped member pivotally secured to said lugs and disposed with legs thereof opposite said passage, a core comprising magnetic material extending through said passage and secured to the opposite legs of said second U-shaped member, said coil being effective upon energization thereof to move 10 said core and to rotate said member about its pivot, and a switch movable between two circuit controlling positions upon tilting thereof mounted on said member.

10. In combination, a winding having a passage 15 therethrough, means for mounting said winding with said passage horizontally disposed, a core comprising magnetic material, means for mounting said core for movement in said passage substantially longitudinally thereof, means biasing 20 said core to a position wherein the magnetic center of said core is displaced from the center of said winding, said winding being effective upon energization thereof to move said core so as to cause the magnetic center of said core to approach 25 the center of said winding, yieldable means to limit the movement of said core due to energization of said coil, and means actuated by said core when so moved.

11. In combination, a winding having a passage 30 therethrough, means for mounting said winding with said passage horizontally disposed, a core comprising magnetic material, means for mounting said core for movement in said passage substantially longitudinally thereof, means biasing 35 said core to a position wherein the magnetic center of said core is displaced from the center of said winding, said winding being effective upon energization thereof to move said core so as to cause the magnetic center of said core to approach 40 the center of said winding, yieldable means to limit the movement of said core due to energization of said coil, said yieldable means being ineffective until said core has moved to substantially its normal energized position, and means 45 actuated by said core when so moved.

12. In a low voltage release relay, a winding having a passage therethrough, means for mounting said winding with said passage horizontally disposed, a core comprising magnetic material, 50 means for mounting said core for movement in said passage substantially longitudinally thereof, means biasing said core to a position wherein the magnetic center of said core is displaced from the center of said winding, said winding being effective upon energization thereof to move said core so as to cause the magnetic center of said core to approach 55 the center of said winding, yieldable means to limit the movement of said core due to energization of said coil, and a switch actuated from a first to a second circuit controlling position by movement of said core.

13. In a low voltage release relay, a winding having a passage therethrough, means for mounting said winding with said passage horizontally disposed, a core comprising magnetic material, 60 means for mounting said core for movement in said passage substantially longitudinally thereof, means biasing said core to a position wherein the

magnetic center of said core is displaced from the center of said winding, said winding being effective upon energization thereof to move said core so as to cause the magnetic center of said core to approach the center of said winding, 5 yieldable means to limit the movement of said core due to energization of said coil, and a switch actuated from a first to a second circuit controlling position by movement of said core, said yieldable means being ineffective until said core has 10 moved to substantially its energized position whereby the voltage required to hold said switch in its second circuit controlling position is not greatly less than that required to move it to said position. 15

14. In combination, a winding having a passage therethrough, means for mounting said winding with said passage horizontally disposed, a rigid U-shaped member having its base portion pivotally mounted above said winding, a core 20 comprising magnetic material extending through said passage and secured to the legs of said U-shaped member, means biasing said member to a position wherein the magnetic center of said core is displaced from the center of said winding, 25 said winding being effective upon energization thereof to move said core and said member so as to cause the magnetic center of said core to approach the center of said winding, means connected to said member and actuated thereby, and 30 resilient means to limit the movement of said core, said resilient means comprising a leaf spring element and an abutment element adapted to cooperate therewith, one of said elements being fixed relative to said winding and the other being 35 carried by one of the legs of said U-shaped member, said abutment and said leaf spring being so spaced that they do not engage until said core has moved to substantially its energized position.

15. In a low voltage release relay, a winding 40 having a passage therethrough, means for mounting said winding with said passage horizontally disposed, a rigid U-shaped member having its base portion pivotally mounted above said winding, a core comprising magnetic material extending through said passage and secured to the legs of said U-shaped member, means biasing said member to a position wherein the magnetic center of said core is displaced from the center of said winding, said winding being effective upon 45 energization thereof to move said core and said member so as to cause the magnetic center of said core to approach the center of said winding, a switch associated with said member and movable from a first to a second circuit controlling position upon movement of said core to its energized 50 position, and resilient means to limit the movement of said core, said resilient means consisting of a leaf spring element and an abutment element adapted to cooperate therewith, one of said 55 elements being fixed relative to said winding and the other being carried by one of the legs of said U-shaped member, said abutment and said leaf spring being so spaced that they do not engage until said core has moved to substantially 60 its energized position.

CARL G. KRONMILLER.
